US00D806662S

(12) **United States Design Patent** (10) **Patent No.:** **US D806,662 S**
Lee et al. (45) **Date of Patent:** **** Jan. 2, 2018**

(54) **TELEVISION**

- (71) Applicant: **Samsung Electronics Co., Ltd.**, Suwon-si (KR)
- (72) Inventors: **Hyungsun Lee**, Yongin-si (KR); **Donggyun Ye**, Seoul (KR); **Woojong Huh**, Yongin-si (KR); **Jeasung Kim**, Hwaseong-si (KR); **Sangyoung Lee**, Anyang-si (KR); **Joonyoung Lee**, Seoul (KR); **Heeseok Jeong**, Suwon-si (KR); **Kyuhyun Cho**, Suwon-si (KR); **Shiyun Cho**, Anyang-si (KR); **Younho Choi**, Seoul (KR)
- (73) Assignee: **Samsung Electronics Co., Ltd.**, Suwon-si (KR)

(**) Term: **15 Years**

(21) Appl. No.: **29/564,924**

(22) Filed: **May 17, 2016**

(30) **Foreign Application Priority Data**

- Nov. 18, 2015 (KR) 30-2015-0058002
- (51) **LOC (11) Cl.** **14-03**
- (52) **U.S. Cl.**
USPC **D14/126**; D14/129
- (58) **Field of Classification Search**
USPC D14/125-134, 239, 371, 374-377, 448, D14/450, 451, 336, 342, 168, 496, 299;

(57) **CLAIM**

We claim the ornamental design for a television, as shown and described.

DESCRIPTION

FIG. 1 is a front perspective view of a television showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion in FIG. 5;

FIG. 9 is a front perspective view of the television shown in another alternate position in which the display panel is partially unfolded;

FIG. 10 is a front view thereof;

FIG. 11 is a rear view thereof;

FIG. 12 is a left-side view thereof;

FIG. 13 is a right-side view thereof;

FIG. 14 is a top view thereof;

FIG. 15 is a bottom view thereof;

FIG. 16 is an enlarged view of the encircled portion in FIG. 13;

(Continued)

FIG. 17 is a front perspective view of the television shown in another alternate position in which the display panel is unfolded;

FIG. 18 is a front view thereof;

FIG. 19 is a rear view thereof;

FIG. 20 is a left-side view thereof;

FIG. 21 is a right-side view thereof;

FIG. 22 is a top view thereof;

FIG. 23 is a bottom view thereof; and,

FIG. 24 is an enlarged view of the encircled portion in FIG. 21.

The broken lines in the figures show portions of the television which form no part of the claimed design.

The dot-dash broken lines encircling enlargement portions of the design form no part of the claimed design.

1 Claim, 21 Drawing Sheets
